UNITED STATES PATENT OFFICE

2,280,740

SOUND RECORDING APPARATUS

Herbert Belar, Philadelphia, Pa., assignor to
 Radio Corporation of America, a corporation of
 Delaware

Application March 30, 1940, Serial No. 326,836

7 Claims. (Cl. 179—100.)

This invention relates to sound recording apparatus, and more particularly to a ground noise reduction amplifier for use in such recording apparatus and the like.

It is known that the transparent unmodulated areas on sound film tend to produce noise during the reproduction of sound due to extraneous materials which may adhere to the surface of the clear portion of the film and due to developed silver grains in the emulsion. The reduction of such noise, by rendering the unmodulated portion of the background or positive film opaque, is described and claimed, for example, in McDowell Reissue Patent No. 21,389. The said patent discloses the use of a rectifying amplifier into which a portion of the audio frequency current is fed. This amplifier, commonly referred to as a ground noise reduction amplifier, rectifies and filters the audio frequency currents producing a direct current which varies in amplitude with the envelope of the sound wave. This varying direct current is then used to control a shutter or other device which causes the blackening of the background in the positive film, as, for example, by producing a transparent background in the negative film so that the background in the positive will be printed opaque.

There have heretofore been difficulties in the construction of such amplifiers due to the fact that the filtering circuit which is capable of filtering out the low audio frequencies necessarily produces a corresponding time delay. This time delay causes, of course, a corresponding delay in the response of the shutter in following the envelope of the sound waves and causes the clipping of the peaks when there is a sudden increase in the amplitude of the sound.

With early equipment, the frequency range was not very great and this clipping did not become serious. However, improvements in the sound recording and film moving equipment have permitted the frequency range of recording to be greatly extended so that the recording of frequencies as low as 50 or even 30 cycles has become customary. The recording of such low frequencies has necessitated the improvement of the filtering in the ground noise reduction amplifier, while, at the same time, the improved quality of the sound reproduction has caused the audiences to become more critical of any defects in the ground noise reduction. Improving the speed of operation of the ground noise reduction apparatus requires the use of less filtering, which is completely inconsistent with the requirement for better filtering due to the increased frequency

range in such a circuit as that disclosed by McDowell, for example.

The apparatus of the present application accomplishes either a speeding up of the operation of the ground noise reduction apparatus, or an improvement of the filtering produced, or both. This result is accomplished by passing the audio frequency input current to the ground noise reduction amplifier through a series of frequency doublers consisting of full wave rectifiers and transformers so that the lowest frequency to be filtered is several times the lowest frequency which is recorded, thereby permitting use of a smaller filter with correspondingly less time delay to secure the same degree of filtering.

One object of the invention is to provide an improved ground noise reduction amplifier.

Another object of the invention is to provide an apparatus which will derive a direct current corresponding to the envelope of an audio frequency current with maximum filtering and at minimum time delay.

Another object of the invention is to provide an amplifier including one or more frequency doublers for increasing the minimum frequency fed to a filter circuit, thereby improving the efficacy of the filter circuit.

Another object of the invention is to provide the sound recording apparatus which will produce a record having better ground noise reduction and higher fidelity of recording than has heretofore been produced.

Other and incidental objects of the invention will be apparent to those skilled in the art from a reading of the following specification and an inspection of the accompanying drawings, in which

Figure 1 is a schematic diagram of one form of the invention in which the direct current output increases on an increase in the audio or A. C. input.

Figure 2 is a schematic diagram of a second form of the invention in which the direct current output decreases on an increase in the audio or A. C. input, and

Figure 3 shows an alternative form of circuit. Similar reference numerals are used in all figures to designate similar parts, and it will be apparent from a comparison of the reference numerals that both circuits are similar as far as the second full wave rectifier.

The audio frequency or other A.-C. input is fed into the apparatus through the transformer 10, the secondary of which is provided with a 10 potentiometer 20 or other equivalent device for

controlling the input to the first amplifier tube 11. Grid bias for the first amplifier tube may be provided by the usual cathode resistor 12 bypassed by the usual cathode condenser 13. The output from the tube 11 is fed through the transformer 14 to the rectifiers 15 and 16, which constitute a full wave rectifier and may be in a common envelope, as, for example, in the type of tube known as the 6H6. The output from the rectifiers 15 and 16 is fed to the primary of the transformer 17 which, like the transformer 14, has a push-pull secondary. It will be apparent that each half wave passing through the transformer 14 will produce a separate impulse in the same direction through the primary of the transformer 17, thereby inducing in the secondary of the transformer 17 alternating currents of twice the frequency of those in the transformer 14. The output from the transformer 17 is fed to a second full wave rectifier 18 and 19 which again may be a type 6H6 tube. It will be apparent that each half impulse from the transformer 17 produces a separate impulse through the rectifiers in the same direction, thereby again doubling the frequency. The output from this second pair of rectifiers is fed into the filter circuit including the capacitors 21, 22 and 23, and the resistors 24, 25 and 26. It will be apparent that if a frequency of, say, 50 cycles is applied to the transformer 10, the input to the filter circuit due to the two doublings will be a pulsating direct current with a pulsation frequency of 200 cycles, which can be smoothed out to its average value by a filter circuit having a much faster time constant than would be the case for the original 50 cycles, if rectified.

In the form of the invention shown in Fig. 1, the grid lead of the amplifier 27 is connected to the cathodes of the rectifiers 18 and 19, and therefore the output of the rectifiers will cause the grid to become more positive, thereby increasing the plate current on an increase of A.-C. input. An appropriate meter 28 may be inserted in the plate circuit of the tube 27 to indicate the D.-C. output and thereby indicate the operation of the ground noise reduction shutter which later may be constructed, for example, in accordance with Baker Patent No. 2,102,776.

In the form of the invention shown in Fig. 2, the cathodes of the rectifiers 18 and 19 are connected to the cathode of the D.-C. amplifier tube 35 through a potentiometer 34, while the center tap of the transformer 17 is connected through the filter circuit to the grid of the tube 35. This filter circuit is quite similar to that shown in Fig. 1 consisting of the capacitors 30 and 31 and the resistors 32, 33 and 34. In this circuit, due to the reversal of connections, an increase in audio input through the transformer 10 causes the grid of the tube 35 to become more negative and the D.-C. output correspondingly decreases on an increase of A.-C. input.

It will be apparent to those skilled in the art that as many doubling stages may be used as are necessary to secure the required speed of operation by decreasing the time constant of the filter circuit.

In the form of the invention shown in Fig. 3, a multiplicity of frequency doubling stages are used, in this case five, which gives a correspondingly high speed of response. However, the use of such a number of doubling stages by themselves is impractical particularly where a wide frequency range is to be handled. For example, in pres-

ent recording it is often desired to record a frequency range from 30 to 10,000 cycles and the input to the transformer 10 would be of that frequency range. The five doubling stages would cause this frequency range to be raised by 2⁵ or the range of output frequencies would become 960 to 320,000 cycles. It will be apparent that the higher frequencies would not be transmitted by the audio frequency transformers used and a separate circuit is therefore used to transmit the higher frequencies.

In the operation of this circuit, the audio frequency input passes through the transformer 10, the potentiometer 20, the amplifier tube 11 and the transformer 14, as in the other forms of the invention. Instead of the single interstage transformer 17 of Figs. 1 and 2, there are provided, however, four such transformers, 17a, 17b, 17c and 17d. In the present case, the full wave rectifier tubes are indicated in the manner conventional for the type 6H6 tubes at 36, 37, 38, 39 and 40 and it will be apparent that the output of the tube 40 will have been doubled in frequency a corresponding number of times, as pointed out above.

A portion of the output from the transformer 10 is also applied to the amplifier tube 53 through the high pass filter including resistors 50 and 51 and the capacitor 52. This high pass filter is designed according to the characteristics of the circuit from the transformer 14 to the tube 40 so that the frequencies of the input to the tube 53 will correspond to those frequencies which have been attenuated or rejected by the doubler circuits. The output of the tube 53 passes through the transformer 56 to the rectifier 57 which, in this case, is shown used as a half-wave rectifier so as to avoid any frequency doubling. The output of the rectifier 57 is passed through the filter circuit including the resistors 59 and 60 and the capacitors 58 and 61 to the output amplifier tube 27 which corresponds to the output tube in the other forms of the invention. It will be apparent that the current passing through this portion of the circuit including the amplifier tube 53 will correspond only to the envelope of the high frequencies without any doubling.

The output from the rectifier tube 40 is passed through the filter circuit including the elements pointed out above and also the capacitor 41 and the resistor 42 in addition to the resistors 59 and 60 and the capacitor 61. Appropriate grid bias may be applied to the tube 27 through the potentiometer 63 which is connected to one side of the plate supply and the resistor 62 which is connected to the other side of the plate supply.

It will be apparent that in this form of the invention all of the lower frequencies will be doubled five times leaving the lowest frequency in the output of the tube 40 something of the order of 900 to 1000 cycles with the other frequencies increasing correspondingly. The frequencies selected by the filter circuit in the upper portion of this circuit and the degree of amplification secured through the amplifier 53 are so chosen that they exactly offset the high frequency losses through the doubler circuits and the output from the tube 27 accordingly corresponds accurately with the envelope of the audio impulses introduced through the transformer 10. This output further is filtered to a very high degree but without any appreciable time lag as the filter circuit in the input to the tube 27 can be made

very small, having no frequencies applied to it of less than about 900 cycles.

It will be apparent that the modification of the apparatus as shown in Fig. 3 can be extended to any desired degree. For example, the first doubling amplifier may have five doubling stages, as illustrated in Fig. 3, and be fed only with the lower group of frequencies. A second doubling amplifier might be fed through a band-pass filter transmitting a group of frequencies slightly higher than those fed through the first doubler and the second doubler having a smaller number of doubling stages, as for example, three. Still a third doubling amplifier may be provided having, for example, only a single doubling stage and likewise fed through a band-pass filter transmitting a higher group of frequencies and the final rectifying amplifier of the group would be small to that shown in the upper portion of Fig. 3 but fed with only the highest audio frequencies which require no doubling.

All the outputs of the rectifying amplifiers in such an arrangement would be combined to provide the desired envelope current preferably being combined through a single filter circuit as shown in Fig. 3 although separate filter circuits could be provided if desired and the outputs thereafter combined in the D.-C. amplifier. The number of doubling amplifiers to be used, the number of doubling stages in each doubling amplifier and the provision of a rectifying amplifier without a doubler must, of course, be chosen with proper regard to the circumstances under which the circuit is to operate. It will be apparent, for example, that an apparatus using a large number of tubes, transformers, etc., would not be adapted for use in a portable equipment where quality must be sacrificed for the sake of portability while, on the other hand, such a portable apparatus would not be entirely satisfactory for studio use where the highest possible quality is necessary and where weight and power requirements are a secondary consideration.

I claim as my invention:

1. An amplifier of the type described having an A.-C. input and a D.-C. output corresponding to the envelope of the A.-C. input, said amplifier including at least one amplifying stage, a filter, and at least one frequency doubler preceding said filter, said filter circuit having such characteristics that it will not properly filter A.-C. input frequencies of the order of 50 cycles but will adequately filter the doubled frequencies applied thereto.

2. An amplifier of the type described having an A.-C. input and a D.-C. output corresponding to the envelope of the A.-C. input, said amplifier including a filter circuit and at least one full wave rectifier serving as a frequency doubler preceding said filter circuit, said filter circuit having such characteristics that it will not properly filter A.-C. input frequencies of the order of 30 cycles but will adequately filter the doubled frequencies applied thereto.

3. An amplifier of the type described having an A.-C. input and a D.-C. output corresponding to the envelope of the A.-C. input, said amplifier including a filter circuit and a plurality of full wave rectifiers serving as frequency doublers preceding said filter circuit, said filter circuit having such characteristics that it will not properly filter A.-C. input frequencies of the order of 30 cycles but will adequately filter the doubled frequencies applied thereto.

4. An amplifier of the type described having an A.-C. input and a D.-C. output corresponding to the envelope of the A.-C. input, said amplifier including a first amplifying stage adapted to amplify the A.-C. input, a plurality of full wave rectifier frequency doubler stages, a filter circuit, and a D.-C. amplifier stage actuated from the output of said filter circuit, said filter circuit having such characteristics that it will not properly filter A.-C. input frequencies of the order of 30 cycles but will adequately filter the doubled frequencies applied thereto.

5. Apparatus of the class described including an amplifier having an A.-C. input and a D.-C. output corresponding to the envelope of the A.-C. input, said amplifier including at least one frequency doubler, rectifying means and output filter means, said apparatus including a second amplifier connected to the same A.-C. input, having a D.-C. output corresponding to the envelope of the A.-C. input and including rectifying means, the output of said second amplifier being connected to the same output filter means as the first amplifier.

35 6. Apparatus of the class described including an amplifier having an A.-C. input and a D.-C. output corresponding to the envelope of the A.-C. input, said amplifier including at least one frequency doubler, rectifying means and output filter means, said apparatus including a second amplifier connected to the same A.-C. input, having a D.-C. output corresponding to the envelope of the A.-C. input and including rectifying means, the output of said second amplifier being connected to the same output filter means as the first amplifier, and high-pass filter means connected between the said A.-C. input and said second amplifier.

50 7. Apparatus of the class described including an amplifier having an A.-C. input and a D.-C. output corresponding to the envelope of the A.-C. input, said amplifier including a plurality of frequency doublers, rectifying means and output filter means, said apparatus including at least one additional amplifier connected to the same A.-C. input, having a D.-C. output corresponding to the envelope of the A.-C. input and including rectifying means and a less number of doublers than the first amplifier, the output of said additional amplifier being connected to the same output filter means as the first amplifier.

HERBERT BELAR.
